UNITED STATES PATENT OFFICE.

HENRY L. LITCHFIELD AND VICTOR SPEER, OF WATERLOO, IOWA; SAID SPEER
ASSIGNOR TO SAID LITCHFIELD.

STRAW-SPREADER.

1,313,637.

Specification of Letters Patent. Patented Aug. 19, 1919.

Application filed March 19, 1918. Serial No. 223,263.

To all whom it may concern:

Be it known that we, HENRY L. LITCHFIELD and VICTOR SPEER, citizens of the United States, residing at Waterloo, county 5 of Blackhawk, State of Iowa, have invented a certain new and useful Improvement in Straw-Spreaders, and declare the following to be a full, clear, and exact description of the same, such as will enable others skilled 10 in the art to which it pertains to make and use the same, reference being had to the accompanying drawings, which form a part of this specification.

Our invention relates to the art of distributing or spreading loose material from a vehicle over a field or other surface across which the vehicle is traveling; and has to do more particularly with the spreaders or distributors adapted to handle straw, manure containing a considerable amount of straw, or other comparatively light, bulky material.

The handling of light, bulky materials, to which we shall hereafter refer simply as straw, introduces problems quite different from those that are encountered in handling ordinary manure and therefore the ordinary manure spreader cannot be used to advantage for this purpose.

One of the special problems is to secure a vehicle box or body which will hold a large quantity of straw and at the same time be capable of being loaded easily and of being drawn or moved about with the same facility as an ordinary farm wagon or spreader. Another problem arises in the breaking up of the load and distributing the comparatively light material on the ground without having it whipped about by the 40 winds before it reaches the ground. The only practicable way in which straw or the like can be handled is to unload from the top of the load and this introduces the further problem of relieving the pressure due to bunches of material and overcoming other conditions which would militate against a regular feed of the material to the ultimate distributing device or mechanism.

Viewed in one of its aspects our invention 50 may be said to have for its object to produce a simple and novel spreader which will permit straw to be handled conveniently in

large quantities and be distributed uniformly over a surface to be covered.

In carrying out our invention we employ 55 a vehicle having a body or rack of large capacity and, in order to keep the top low enough to permit convenient loading, secure stability and prevent swaying and bring the discharge point for the straw close to the 60 surface over which a vehicle is traveling, we make the rack much wider than the ordinary manure spreader, or substantially as wide as the ordinary hay or straw rack used on farms; and we mount the rack on a bed sup- 65 ported on wheels whose tread is as wide as or wider than the rack in such a manner that the bed comes close to the ground and all four corners are required to move up and down with the corresponding wheels. In or- 70 der to bring the bed of the vehicle close to the ground, it is necessary that it be underslung and that wheels of comparatively small diameter be employed. We secure capacity for short turning movements as 75 well as substantially the same rigidity of support for the two front corners of the rack as is obtained at the rear corners, by eliminating the usual fifth wheel and mounting the journals for the front wheels so that 80 they may turn about vertical axes passing through the ends of the front axle. Therefore, viewed in one of its aspects, our invention may be said to have for its object to produce a simple and novel form of ve- 85 hicle of the wagon type which shall be capable of holding and conveying large quantities of loose bulky material, possess great stability, be flexible in operation, and be low enough to make loading easy and un- 90 loading practical, and to maintain a broad, stable, supporting base adapted to the peculiar needs of vehicles of the nature specified.

For the purpose of unloading the straw 95 we employ a swinging frame having thereon an endless rake or toothed conveyer which rakes off the top of the load and delivers it to a beater wheel which discharges the straw upon the ground. Other objects of 100 our invention are to produce a simple and novel construction which will permit the employment of a swinging conveyer frame considerably shorter than the length of the

rack, so that when the conveyer frame stands in an upright position, it does not bring the center of gravity of the spreader so high as to interfere with its stability; to provide for 5 automatically raising and lowering the conveyer frame and for both automatically and manually controlling the raising and lowering operations; to provide for automatically varying the rate at which the conveyer is 10 fed into the work in order to compensate for the varying conditions that are encountered as the distribution progresses; to insure against clogging of the working parts by reason of bunching straw or straw which 15 wraps itself about rotating parts; and provide an arrangement of pins or teeth on the conveyer and guards and relieving springs between the conveyer and the beater wheel which will insure that the straw will be delivered regularly to the beater wheel in a 20 fluffy condition and be thoroughly scattered by the beater wheel.

The various features of novelty whereby our invention is characterized will herein-after be pointed out with particularity in 25 the claims; but, for a full understanding of our invention and of its objects and advantages, reference may be had to the following detailed description taken in connection 30 with the accompanying drawings, wherein:

Fig. 1 is a side elevation of a spreader arranged in accordance with a preferred form of our invention, showing the conveyer frame lowered about halfway;

Fig. 2 is a view similar to Fig. 1, on an enlarged scale, showing only the rear end of the spreader;

Fig. 3 is a rear elevation of so much of the spreader as is shown in Fig. 2;

Fig. 4 is a rear elevation of the rack with the conveyer frame and its supporting cables for the frame, parts being omitted and other parts being broken away for the sake of clearness;

Fig. 5 is a central vertical longitudinal section through the rear end of the spreader, looking from the right toward the left in Fig. 3;

Fig. 6 is a section taken approximately on line 6—6 of Fig. 3, the beater wheel and some of the driving mechanism being omitted;

Fig. 7 is a top plan view of the parts shown in Fig. 6;

Fig. 8 is a top plan view of the rear end of the spreader, the conveyer and conveyer frame and operating means therefor being omitted;

Fig. 9 is a section taken approximately on line 9—9 of Fig. 1; and

Fig. 10 is a detail showing an element of the clutch on the main counter-shaft and a portion of one of the differentials between the counter-shaft and one of the rear wheels 65 of the spreader.

Referring to the drawings, 1 represents an approximately rectangular bed or frame, preferably made of structural steel, as illustrated, hung beneath front and rear axles, 2 and 3. On the front axle are wheels, 4, 4, 70 mounted on axle extensions, 5, 5, which swing about vertical pivots, 6, 6. On the rear axle are wheels, 7, 7. The frame together with the wheeled axles, both of the latter of which are much longer than the 75 ordinary wagon axle, form a low wheeled structure which may be turned sharply by reason of the capacity of the front wheels to turn about the vertical pivots.

As will be seen in Fig. 9, the two axle 80 members 5 are provided with forwardly projecting arms, 8, 8, which are connected to a wagon tongue, 9, by means of rods or links, 10, 10. With this arrangement, the wheels are caused to turn about their pivots 85 when the wagon tongue is swung toward one side or the other from a central position.

Arranged upon the supporting frame is a deep body or rack, 11, having an approximately horizontal bottom, 12, and being 90 open at the top and at the rear. At the front end of the rack, adjacent to the right hand side is a driver's seat, 13.

Just behind the rear end of the rack and at a short distance above the plane of the 95 bottom or floor of the latter is a transverse horizontal shaft, 14, on which is mounted one end of a rectangular frame, 15, having a length considerably less than the length of the rack and a width sufficiently less than 100 the interior width of the rack to permit the frame to swing easily from an approximately vertical position at the rear of the rack into an approximately horizontal position just above the floor of the rack. The 105 front end of the rack is peculiarly shaped, there being a downwardly and rearwardly inclined wall, 16, extending from a point about halfway down from the top of the rack to the bottom or floor and joining the latter 110 in proximity to the position which the front end of the swinging frame occupies when the latter is completely lowered. Thus the front end of the body or rack forms with the imaginary surface of revolution of the front end of the rectangular frame a space of 115 considerable capacity becoming gradually narrower toward the bottom; permitting a considerable body of straw to be carried beyond the front end of the swinging frame 120 and to be fed thereto automatically as the load is raked away as will be hereinafter described. In other words, by this simple expedient it becomes possible to employ a swinging frame which is much shorter than 125 the effective length of the body or rack; thus not only making the apparatus lighter, but adding considerably to the stability of the spreader when the swinging frame is in an upright position. The swinging frame has 130

- a broad flat transverse board or plate, 17, extending across the same just above or in front of the shaft 14 so as to act as a shield or guard, as will hereinafter be explained, 5 to prevent straw from becoming wrapped around the shaft when the machine is in operation. On the shaft 14 are a series of sprocket wheels, 18, illustrated as three in number; one of the sprocket wheels being at 10 approximately the longitudinal center of the frame and the other two being in alignment with the side members of the frame. At the free end of the frame are sprocket wheels, 19, equal in number to the sprocket 15 wheels 18, and similarly spaced. Endless sprocket chains, 20, extend longitudinally above and underneath the frame, each passing around one of the sprocket wheels 18 and the corresponding sprocket wheel 19. 20 The chains are connected together by a series of transverse cross bars or slats, 21, provided with outwardly projecting pins or teeth, 22. The pins or teeth, for a purpose to be hereinafter explained, are preferably 25 not made of uniform length throughout the conveyer, some of them being preferably made longer than others. The two side members of the swinging frame are provided with or constitute tracks or rails on 30 which the upper halves of the two side chains lie. Beneath the intermediate chain there is preferably a central track or rail, 23. The side members of the swinging frame are provided with upwardly projecting ledges, 35 24, along their outer edges, to prevent lateral displacement of the conveyer. While the upper half of the conveyer rests upon tracks or rails, the under half hangs loosely as shown. 40 The swinging conveyer frame is provided near its front end at opposite sides thereof, with guiding shoes, 25, which are adapted to engage with the inner sides of the side walls of the rack to guide the free end of the 45 frame in its up and down movements.
- The swinging frame is supported as follows: Above and somewhat in rear of the shaft 14 is a horizontal transverse shaft, 27, on each end of which is an elongated 50 spool, 28. Cables, 29, each attached at one end to one of the spools, pass upwardly over elongated rollers, 30, each supported above one of the spools 28, preferably at a level higher than the top of the rack, 55 each having a length about equal to the length of one of the spools. Each of the cables, after passing over one of the rolls, is carried around a pulley or wheel, 31, mounted on the corresponding side member 60 of the swinging frame, then back over a wheel or pulley, 32, lying co-axial with one of the rollers 30 and in the plane of the corresponding wheel or pulley 31. From the pulleys or wheels 32, the cables pass 65 to suitable anchoring points, 33, on the
- side members of the swinging frame. It will be seen that with this arrangement, the anchoring point of each cable moves only one-third as fast as the opposite end which is attached to one of the spools when the 70 shaft carrying the spools is rotated. A suitable brake or counter-balancing device is associated with the spool shaft so that the weight of the swinging frame and its conveyer will not be sufficient to unwind the 75 cables from the spools. In the arrangement shown, see Fig. 5, the shaft 27 is supported between a pair of separated bearing blocks, 34, between which the shaft 27 may be clamped with any desired degree of pressure by means of clamping bolts, 35. 80
- It will be noted that the spools 28 decrease gradually in diameter from their outer ends toward their inner ends to which the ends of the cables are attached. Thus, 85 when the cables are completely wound up on the spools, that is when the swinging frame is upright, the first turns to be unwound upon any subsequent lowering of the frame are those of large diameter at the 90 large ends of the spools; as the lowering of the frame proceeds, it is at a gradually decreasing speed for a given speed of the spool supporting shaft 14.
- In rear of the lower rear end of the 95 swinging frame is placed a beater wheel, 37, mounted on a horizontal shaft, 38, which preferably lies at some distance above the plane of the bottom or floor 12 of the rack. The beater wheel is of any usual type, 100 but preferably has radially projecting pins or teeth, 39, distributed lengthwise and circumferentially of the same, the teeth being alternately long and short. There is a considerable gap between the rear end of the 105 floor or bottom of the rack and the beater wheel, and this gap is bridged by a comb constituting a series of resilient parallel fingers, 40, projecting rearwardly into proximity to the beater wheel. This comb 110 forms a yielding bottom which will permit the escape of any lump or large object which might otherwise clog the working mechanism. A second comb preferably made of a series of metal bars, 41, is arranged on edge in front of the beater wheel 115 and extends from a transverse support, 42, above the beater wheel, to which support the fingers are attached, into proximity to the rear ends of the fingers 40. The comb composed of the fingers 41 serves as a guard to prevent the straw from being packed 120 upon the beater wheel, serving to arrest the straw while permitting the passage of the teeth of the beater wheel through the same 125 and into the mass of straw lying against it.
- The shafts 14, 27 and 38 are all driven from the rear wheels of the spreader. In the arrangement shown, we have mounted on the frame of the spreader in rear of the 130

rear axle a counter-shaft, 44. To each of the rear wheels is fixed a large driving sprocket, 45, over which passes a sprocket chain, 46, engaging with a sprocket wheel, 47, loose on the shaft 44 but connected therewith in such a way that when the spreader is moving ahead and both of the rear wheels are revolving at the same speed, the two sprocket wheels 47 will be clutched to the shaft 44 and will coöperate in driving it; while, on the other hand, if one of the rear wheels of the spreader is rotating more rapidly than the other, the corresponding sprocket wheel on the shaft 44 will serve as the driving member and the other sprocket wheel will simply lag behind. This may conveniently be accomplished by hinging to some member, 48, fixed to the shaft 44 a spring-held arm or pawl, 49, having a shoulder adapted normally to lie in the path of the lug 50 on the corresponding sprocket wheel; the parts being so proportioned that when the sprocket wheels are rotated, during the forward movement of the spreader, the lugs 50 engage the shoulders on the arms or pawls, 49, from the rear and thus drive the shaft 44 ahead.

The member 48 on the right hand side of the spreader is provided on its outer side face with clutch teeth, 51, adapted to coöperate with complementary clutch teeth on a sprocket wheel, 52, slideable lengthwise of the counter-shaft. It will be seen that whenever the spreader is moving forward, the counter-shaft will be revolving and therefore, by providing suitable connections between the sprocket wheel 52 and the various shafts to be driven, the rotation of these latter shafts may be controlled by simply shifting the sprocket wheel 52 into and out of clutching engagement with the corresponding member, 48, fixed to the counter-shaft. The sprocket wheel 52 may be shifted into and out of a working position in any suitable way, preferably through suitable connections from a lever, 53, mounted on the side of the rack within easy reach of the driver in the driver's seat, 13. Since these connections are well known mechanical expedients, I shall not describe them in detail but on the drawings indicate them as a whole by the reference characters 54 and 55.

On the shaft 14 is a sprocket wheel, 56, in the same plane as the sprocket wheel 52, and a sprocket chain, 56^a, passes over these two sprocket wheels. Fixed to the shaft 14 is a second sprocket wheel, 57, while on the shaft, 38, of the beater wheel is a small sprocket wheel, 58. A sprocket chain, 59, passing over the sprocket wheels 57 and 58 forms the driving connection between the shaft 14 and the beater wheel shaft. It will be seen that when the clutch is thrown in

by the driver so as to cause the sprocket wheel 52 to rotate, the driving shaft for the endless conveyer and also the beater wheel shaft are set into rotation, the direction of rotation being the same as the direction in which the rear wheels of the spreader are rotating.

It is desirable that the raking conveyer be lowered into the straw by a step by step movement which may be controlled to give any desired rate of feed, and it is also desirable that the lifting of the conveyer frame take place with a considerable degree of rapidity and preferably by a continuous movement. To this end we have provided two separate driving connections between the spool shaft, 27, and the shaft 14. One of these driving connections comprises a sprocket chain, 61, passing over a sprocket wheel, 62, fixed to the shaft 14, and a sprocket wheel, 63, loose on the spool shaft 27. The sprocket wheel, 63, has on its outer side face clutch teeth, 64, adapted to be engaged by complementary teeth on a clutch sleeve, 65, slideable lengthwise of the shaft 27 but held against rotation relatively thereto. In Fig. 3, the clutch sleeve is shown out of coöperative relation with the clutch teeth, 64, but if the sleeve be moved toward the left, the sprocket wheel 63 will be clutched to the shaft 27 and the latter will be turned in the same directions as the shafts 14 and 38 when the spreader is traveling ahead.

The step by step rotation of the shaft 27 is obtained as follows: On the shaft is loosely arranged a ratchet wheel, 66, so positioned that the clutch sleeve lies between it and the sprocket wheel 63. The ratchet wheel has clutch teeth, 67, on the face next to the clutch sleeve, these teeth being adapted to coöperate with complementary teeth on the clutch sleeve. On the rack, in the plane of the ratchet wheel, is mounted a swinging arm, 68, on which is carried a double pawl device, 69, adapted to engage the teeth on the ratchet wheel and turn the latter step by step when the arm 68 is swung about its pivot. The arm 68 is connected to an eccentric strap, 70, surrounding an eccentric, 71, fixed to the shaft 14. Therefore, as the shaft 14 revolves, the eccentric oscillates the arm 68 and actuates the ratchet wheel. The angle through which the ratchet wheel is turned during each revolution of the eccentric depends upon the distance between the pivotal axis of the swinging arm 68 and the point of attachment of the double pawl device to this arm. The connection between the arm and the double pawl device is through a shoe or head, 72, which is slideable lengthwise of the arm and adapted to be held in any one of various adjusted positions by means of a pin, 73, extending through any one of a series of holes, 74, distributed lengthwise of the arm. The parts are so

proportioned that the ratchet wheel is rotated in the opposite direction from that in which the rear wheels of the spreader, and consequently the shafts 14 and 38 rotate. 5 Therefore, when the ratchet wheel is clutched to the shaft 27, the latter is turned in the opposite direction from that in which the sprocket connections drive it; this being in the direction to unwind the cables and 10 permit the swinging frame to be lowered gradually.

It will be seen that when the clutch sleeve on the spool shaft 27 is in a neutral position, out of clutching relation with both the 15 sprocket wheel 63 and the ratchet wheel 66, the spool shaft will remain idle while the spreader is traveling and the brake will hold it against rotation, so that the swinging conveyer frame will remain in whatever position 20 it may at the moment be occupying. Suitable operating connections for the clutch sleeve, including a hand lever, 76, within easy reach of a driver sitting in the driver's seat, permit the driver to control the swinging movements of the frame at will. It is 25 desirable to have not only manual controlling means for stopping the movement of the swinging frame but also automatic stopping means which will cause it to come to rest whenever either the upper or downward 30 limit of its movement is reached. We have therefore combined with the manual controlling device for the clutch sleeve automatic controlling means which will always 35 cause the clutch sleeve to be brought to its neutral position whenever the frame has been swung completely up or down. In the arrangement shown, as will be best seen from Figs. 3, 6 and 7, the clutch sleeve is operated 40 by a fork or yoke, 77, on the lower end of an upright rotatable rod, 78. On the upper end of the rod is a laterally projecting actuating arm, 79. Between the arm 79 and the hand lever 76 at the driver's seat is 45 an actuating bar, 80, connected at its front end to the lever and having at its rear end a suitable connection with the arm 79 as for example, an eye, 81, through which the arm 79 is slipped. The arm 79 is preferably 50 hinged to the upper end of the rod 78 so that it may swing about a horizontal axis and rides over a notched segment, 82; being 55 yieldingly held in contact with this segment by a spring, 83. The segment preferably has 60 three notches, one for the neutral position of the clutch sleeve and one for each of the working positions of the latter and the parts are so arranged that the actuating arm 79 and the notches in the segment will yieldingly 65 hold the clutch sleeve in any one of its three positions into which it may be brought but will permit the clutch sleeve to be shifted when a predetermined turning pressure is brought to bear in the actuating arm. 70 The automatic shifting of the clutch sleeve

is produced by some suitable connection between the actuating arm 79 and the swinging frame. In the arrangement shown, the actuating arm 79 is connected to a swinging arm, 84, parallel therewith and movable 70 about an axis parallel with the rod 78; a link, 85, connecting the free ends of the arms 79 and 84 together. On the swinging frame is a projecting post or the like, 86, which, when the frame swings in an upright position, engages with the arm 84 and shifts it far enough to cause the clutch sleeve to be brought into its neutral position. A chain, 87, or other flexible member, is connected at one end to the arm 79 and, after passing 80 across the top of the arm 84 which serves the purpose of a guide, it is attached to the swinging frame at such a point that when the latter is approaching the lower limit of its swinging movement, the chain will be 85 drawn taut, causing the clutch controlling shaft, 78, to be turned and the clutch sleeve to be shifted into its neutral position when the swinging frame reaches such lower limit of its movement. 90

In the drawings the swinging conveyer frame is shown making an angle of about forty-five degrees to the horizontal but when the spreader is empty and it is to be loaded, the frame will be placed in an upright position, forming, in effect, the rear wall of the 95 rack. By reason of our peculiar construction, which secures great capacity by bringing the rack low to the ground and making it as wide as will permit the spreader to 100 pass through the ordinary farm gate, the top of the rack is low enough to permit the loading to be done by one man. After the rack has been loaded, the clutches being thrown out, the spreader may be drawn to 105 the field where the straw is to be distributed, in the same way as an ordinary loaded wagon. By reason of the broad wheel base and the comparatively low center of gravity, the loaded spreader is very stable and it will 110 travel smoothly and without danger of tipping over even under the most awkward conditions. The stability is further increased by reason of the fact that there is no fifth wheel which permits the load to 115 rock or sway on its supports. Short turns may be made with absolute safety because of the manner in which the front or steering wheels are mounted.

When the field over which the straw is to 120 be distributed is reached, the pawl and ratchet lowering mechanism for the conveyer frame having first been properly adjusted, the main clutch is thrown in and the clutch sleeve on the spool shaft is engaged 125 with the ratchet wheel. All shafts, except the spool shaft, will now be rotated in the same direction as the rear wheels of the spreader; the result being that that portion of the raking conveyer in engagement with 130

the straw begins to travel down, tearing quantities of straw loose from the mass and finally delivering them in front of the beater wheel; the beater wheel revolves rapidly in 5 a direction to discharge the straw downwardly between it and the rear end of the rack; and the spool shaft is rotated slowly, step by step, overcoming the resistance of the brake and permitting the conveyer frame 10 to descend upon the load through the action of gravity. The two combs or sets of guard fingers serve not only to prevent the mechanism from being clogged, but they also co-operate with the pins or teeth on the beater 15 wheel to tear apart the straw as it comes from the traveling rake; so that the straw, when it finally leaves the spreader, has been thoroughly loosened up so that an even spread of straw may be obtained if it can be 20 caused to reach the ground without being carried out of the path into which it is thrown by the beater wheel. The floor of the rack is only a short distance above the ground and the beater wheel extends even 25 closer to the ground. Consequently the straw has only a short distance to travel after it leaves the beater wheel and, since it is moving at a high speed, its direction will be unchanged by winds which may be 30 blowing. This is of great importance because of the lightness of straw compared to its superficial area, the momentum which can be given to the straw by the beater wheel will not be sufficient to prevent the straw 35 from being whipped out of its course by the wind if the straw has to travel very far before reaching the ground.

The top of the load is comparatively light and fluffy but, as the bottom is approached, 40 the density increases. Consequently, in order to discharge the straw at a constant rate, the speed at which the traveling rake is lowered must be varied as the distribution progresses. This is accomplished by the 45 peculiarly shaped spools which cause the cables to be unwound at a gradually decreasing rate during the first portion of the downward movement of the swinging rake. In addition to the increasing density, there is 50 also the factor of that section of the load which lies in front of the arc which the front end of the swinging rake describes. As the rake is lowered into the load, this body of straw in the front end of the rack progressively 55 drops down within reach of the traveling rake; the inclined front end in the lower half of the rack insuring that all of the straw in the front end of the rack will be fed down to the rake.

60 We have found that it is advantageous to make the teeth of the rake of various lengths, the longer teeth entering well into the mass of straw and tearing or fluffing the surface, the loosened straw being then carried along 65 by the shorter teeth. The step by step low-

ering of the rake is also an advantage because it gives a chattering or jarring contact between the rake and the load which insures proper penetration of the teeth and uniform feeding.

As the swinging conveyer frame approaches a horizontal position, the chain between the frame and the actuating mechanism for the clutch sleeve on the spool shaft is drawn taut and finally, when the frame 70 reaches a position which will permit the last of the straw to be raked along the floor of the rack, the clutch sleeve will be shifted into a neutral position and the spool shaft 75 will cease rotating. On his way to the loading point, the driver, without leaving his seat, shifts the clutch sleeve on the spool shaft so as to clutch the sprocket wheel to the shaft. Then, while the spreader is traveling ahead, the spool shaft will be automatically turned in the proper direction to wind up the cables and raise the swinging frame. When the swinging frame reaches 80 its approximately upright position the post or tripping device on the frame strikes the actuating arm for the clutch sleeve on the spool shaft, shifting it in the opposite direction from that in which it is carried by the chain as the swinging frame reaches the lower limit of its movement, causing the 85 clutch sleeve to be thrown into its neutral position and the spool shaft to be stopped.

The supporting frame for the rack, the rack, and the swinging frame carrying the raking conveyer are all so jointed that they 100 will yield as the spreader travels over rough ground, so as to accommodate themselves to the surface irregularities without introducing injurious strains or causing the swinging structure to bind.

While we have illustrated and described with particularity only a single preferred form of our invention, we do not desire to be limited to the exact structural details thus illustrated and described; but intend to cover all forms and arrangements which come within the terms employed in the definition of our invention constituting the appended claims.

We claim:

1. A vehicle comprising a broad, deep body or rack underslung from front and rear supporting wheels so as to bring the bottom thereof close to the ground, a long frame hinged at one end to the rear end of the body or rack so as to be capable of swinging from an approximately upright position into a position approximately parallel with and adjacent to the body or rack, raking mechanism carried by said frame for feeding the top of the load toward the rear, and means at the rear end of the body or rack for receiving material from said raking mechanism and discharging it directly downward upon the ground.

2. In a spreader, front and rear pairs of wheels, the wheels of each pair being spread apart more widely than in the ordinary farm wagon, a frame hung from said wheels and 5 lying below the axes thereof, a broad deep body or rack supported by said frame and thus having its bottom brought close to the ground, means for feeding material in the body or rack toward one edge of said bottom, and means in proximity to said edge 10 adapted to act on the material as it passes over said edge and assist the action of gravity in causing said material to fall directly upon the ground.
- 15 3. In a spreader, front and rear pairs of wheels, the wheels of each pair being spread apart more widely than in the ordinary farm wagon, a frame hung from said wheels and lying below the axes thereof, a broad 20 deep body or rack supported by said frame and thus having its bottom brought close to the ground, means for feeding material toward one edge of the bottom of said body or rack, and a beater wheel arranged in proximity to said edge and adapted to rotate in a direction to act on the material as it passes over said edge to assist the action of gravity in causing such material to fall directly upon the ground.
- 25 4. A vehicle comprising a wheeled body or rack, distributing mechanism including an endless rake having a width approximately equal to the width of the body or rack and a length considerably less than the length of the latter, said rake being mounted so as to be capable of swinging bodily about an axis 30 passing through one end of the same in proximity to one end of the bottom of the body or rack, and the lower portion of the wall of the body or rack opposite the aforesaid end being inclined so that the path of movement of the front end of the rake and said portion converge downwardly from points in a horizontal plane above a similar 35 plane passing through the upper run of the rake when the latter is in its lowermost position.
- 40 5. A vehicle comprising a wheeled body or rack open across the rear in the vicinity of the bottom thereof, a structure considerably shorter than the length of the upper portion of the body or rack movable downwardly through the body or rack and provided with means for engaging with the top 45 of the load and feeding it toward the open end, and the front wall of said body or rack being constructed to form with the path of movement of the front end of said raking structure a space extending across the body 50 or rack and narrowing progressively from the top toward the bottom.
- 55 6. A vehicle comprising a wheeled body or rack open across the rear in the vicinity of the bottom thereof, a swinging structure arranged in said body or rack and support- 60 ed so as to swing about a transverse axis in the vicinity of the bottom at the rear end, said swinging structure having thereon an endless traveling rake, and the front wall of said body or rack being shaped to form 70 with the path of travel of the front end of the rake a space extending across the width of the body or rack and narrowing progressively from the top toward the bottom, a portion of said front wall extending from 75 the bottom to a point above the lowermost position of the rake being inclined abruptly toward the rear.
7. A vehicle comprising a wheeled body or rack so constructed as to bring the bottom thereof close to the ground, the rear of the body or rack in the vicinity of the bottom being open, the front end of the body or rack being gradually inclined downwardly and rearwardly, a swinging structure of approximately the width of the body or rack and of a length less than the length of the top of the latter mounted so as to swing about a transverse axis passing through one end thereof in the vicinity of said open end 80 so as to swing from an approximately upright position into an approximately horizontal position adjacent to the bottom of the body or rack, and an endless rake on said structure adapted to engage with the top of 85 the load and feed it toward the open end of the body or rack, said front wall forming with the imaginary surface of revolution of the front end of said swinging structure a funnel-shaped space of considerable capacity.
- 90 8. A vehicle comprising a wheeled body or rack so constructed as to bring the bottom thereof close to the ground, the rear of the body or rack in the vicinity of the bottom being open, the front end of the body or rack being gradually inclined downwardly and rearwardly, a swinging structure of approximately the width of the body or rack and of a length less than the length of the top of the latter mounted so as to swing about a transverse axis passing through one end thereof in the vicinity of said open end so as to swing from an approximately upright position into an approximately horizontal 95 position adjacent to the bottom of the body or rack, an endless rake on said structure adapted to engage with the top of the load and feed it toward the open end of the body or rack, and a beater wheel at the rear end 100 of said body or rack adapted to receive the material raked from the load and discharge it downwardly in front of the same.
- 105 9. A vehicle comprising a wheeled body or rack open across the rear in the vicinity of the bottom thereof, a structure of approximately the same length as the bottom of the body or rack movable downwardly through said body or rack and provided with means for engaging with the top of the 110
- 115
- 120
- 125
- 130

load and feeding it toward the open end, the front wall of the body or rack being inclined forwardly from the bottom thereof to a point far above said structure when the latter is in its lowermost position so as to provide in the front end of the body or rack a space of considerable capacity narrowing toward the bottom to permit the material contained in said space to feed downwardly by gravity into position to be engaged by the feeding means.

10. The combination with a vehicle, of a mechanism adapted to rake the top of the load toward one edge of the vehicle, and means for automatically lowering said mechanism step by step.

11. The combination with a vehicle, of a mechanism adapted to rake the top of the load toward one edge of the vehicle, and means for automatically lowering said mechanism at a speed decreasing gradually.

12. The combination with a vehicle, of a mechanism adapted to rake the top of the load toward one edge of the vehicle, and means for automatically lowering said mechanism at a speed varying inversely with the density of the load.

13. The combination with a vehicle, of a mechanism adapted to rake the top of the load toward one edge of the vehicle, and means for automatically lowering said mechanism at a speed variable in such a manner that material is removed from the load at a substantially uniform rate.

14. The combination with a vehicle, of a mechanism adapted to rake the top of the load to one edge of the vehicle, means for gradually lowering said mechanism as the load diminishes and thus maintain said mechanism in operative relation to the load, and means for varying the rate at which the raking mechanism is lowered relatively to the raking speed.

15. The combination with a vehicle, of a mechanism adapted to rake the top of the load to one edge of the vehicle, means for gradually lowering said mechanism as the load diminishes and thus maintain said mechanism in operative relation to the load, and means for automatically varying the rate at which the raking mechanism is lowered relatively to the raking speed so as to cause material to be raked from the load at a rate which is not dependent upon the varying conditions in the load as the unloading progresses.

16. The combination with a vehicle, of a mechanism adapted to rake the top of the load toward one edge of the vehicle, means for actuating said mechanism from the movement of the vehicle, and means for lowering said mechanism at a speed which is automatically decreased.

17. The combination with a vehicle, of a mechanism adapted to rake the top of the

load toward one edge of the vehicle, tapering spools, cables wound on said spools and connected at their free ends to said mechanism, and means for rotating said spools.

18. The combination with a vehicle, of a mechanism adapted to rake the top of the load toward one edge of the vehicle, tapering spools, cables wound on said spools and connected at their free ends to said mechanism, and means for rotating said spools through the movement of the vehicle.

19. The combination with a vehicle, of a mechanism adapted to rake the top of the load toward one edge of the vehicle, tapering spools, cables wound on said spools and connected at their free ends to said mechanism, and means for rotating said spools step by step for the purpose of lowering said mechanism.

20. The combination with a vehicle, of a mechanism adapted to rake the top of the load toward one edge of the vehicle, means for automatically lowering said mechanism step by step as the load diminishes, and means for raising said mechanism through a continuous movement.

21. The combination with a vehicle, of a mechanism adapted to rake the top of the load toward one edge of the vehicle, means for automatically lowering said mechanism at a variable speed, and means for raising said mechanism at a uniform speed.

22. The combination with a vehicle, of a mechanism adapted to rake the top of the load toward one edge of the vehicle, means for automatically lowering said mechanism step by step at a variable speed, and means for raising said mechanism at a uniform speed.

23. The combination with a vehicle, of a mechanism adapted to rake the top of the load toward one edge of the vehicle and tending to follow the load downwardly by gravity, a holding device normally restraining such mechanism against its tendency to travel downwardly, and means for overcoming the restraining influence of said holding device to permit gravity to act on said mechanism and lower the same.

24. The combination with a vehicle, of a mechanism adapted to rake the top of the load toward one edge of the vehicle and tending to follow the load downwardly by gravity, a holding device normally restraining such mechanism against its tendency to travel downwardly, and means controlled by the movement of the vehicle for intermittently overcoming the restraining influence of said holding device to permit said mechanism to be lowered step by step.

25. The combination with a vehicle, of a mechanism adapted to rake the top of the load toward one edge of the vehicle and tending to follow the load downwardly by gravity, a holding device normally restrain-

ing such mechanism against its tendency to travel downwardly, and means controlled by the movement of the vehicle for overcoming the restraining influence of said holding device to permit gravity to act on said mechanism and lower the same.

26. The combination with a vehicle, of a mechanism adapted to rake the top of the load toward one edge of the vehicle and tending to follow the load downwardly as the latter diminishes, a rotatable shaft, supporting cables extending between said mechanism and said shaft and wound on the latter, a holding device for normally restraining said shaft against the tendency of said mechanism to unwind the cables therefrom, and means for turning said shaft against the resistance of said device to permit said mechanism to follow down after the diminishing load.

27. The combination with a vehicle, of a mechanism adapted to rake the top of the load toward one edge of the vehicle and tending to follow the load downwardly as the load diminishes, a rotatable shaft, supporting cables extending between said mechanism and said shaft and wound on the latter, a brake for holding said shaft against the tendency of said mechanism to rotate it and unwind the cables therefrom, and means for turning said shaft against the resistance of said brake.

28. The combination with a vehicle, of a mechanism adapted to rake the top of the load toward one edge of the vehicle and tending to follow the load downwardly as the load diminishes, a rotatable shaft, supporting cables extending between said mechanism and said shaft and wound on the latter, a brake for holding said shaft against the tendency of said mechanism to rotate it and unwind the cables therefrom, and means controlled by the movement of the vehicle for turning said shaft against the resistance of the brake.

29. The combination with a vehicle, of a mechanism adapted to rake the top of the load toward one edge of the vehicle and tending to follow the load downwardly as the load diminishes, a rotatable shaft, supporting cables extending between said mechanism and said shaft and wound on the latter, a brake for holding said shaft against the tendency of said mechanism to rotate it and unwind the cables therefrom, and means controlled by the movement of the vehicle for turning said shaft step by step against the resistance of the brake.

30. The combination with a vehicle, of a mechanism adapted to rake the top of the load toward one edge of the vehicle and tending to follow the load downwardly as the load diminishes, a rotatable shaft, supporting cables extending between said mechanism and said shaft and wound on the

latter, a brake for holding said shaft against the tendency of said mechanism to rotate it and unwind the cables therefrom, and means controlled by the movement of the vehicle for turning said shaft in one direction to cause said mechanism to be lowered and in the opposite direction to cause said mechanism to be raised.

31. The combination with a vehicle, of a mechanism adapted to rake the top of the load toward one edge of the vehicle and tending to follow the load downwardly as the load diminishes, a rotatable shaft, supporting cables extending between said mechanism and said shaft and wound on the latter, a brake for holding said shaft against the tendency of said mechanism to rotate it and unwind the cables therefrom, and means controlled by the movement of the vehicle for turning said shaft step by step against the resistance of the brake in a direction to permit the cables to be unwound and for rotating the shaft continuously in the direction to wind up the cables when it is desired to raise said mechanism.

32. The combination with a vehicle, of a mechanism adapted to rake the top of the load toward one edge of the vehicle and support it so as to be movable downwardly by gravity, a brake for normally holding said mechanism against downward movement, and means controlled by the movement of the vehicle for overcoming the resistance of said brake and permitting said mechanism to move downwardly at a gradually decreasing speed.

33. The combination with a vehicle, of a mechanism adapted to rake the top of the load toward one edge of the wheeled vehicle and support it so as to be movable downwardly by gravity, a rotatable shaft, supporting cables extending between said mechanism and said shaft and wound on the latter, driving mechanism between the wheels of the vehicle and said shaft for turning it continuously in one direction, driving mechanism between said wheels and said shaft for turning said shaft step by step in the opposite direction, and means for bringing either of said driving mechanisms into operative relation to the shaft and the other driving mechanism into an inoperative relation to the shaft.

34. The combination with a vehicle, of a mechanism adapted to rake the top of the load toward one edge of the wheeled vehicle and support it so as to be movable downwardly by gravity, a rotatable shaft, supporting cables extending between said mechanism and said shaft and wound on the latter, driving mechanism between the wheels of the vehicle and said shaft for turning it at a uniform rate in one direction, driving mechanism between said wheels and said

shaft for turning said shaft at a variable rate in the opposite direction, and means for bringing either of said driving mechanisms into operative relation to the shaft and the 5 other driving mechanism into an inoperative relation to the shaft.

35. The combination with a vehicle, of a mechanism adapted to rake the top of the load toward one edge of the vehicle, means 10 for lowering said mechanism, means for raising said mechanism, a clutch device for connecting said mechanism with each of said means, a lever within reach of the driver of the vehicle for actuating said clutch device, and means associated with said mechanism for automatically shifting said clutch device into a neutral position when the upper and lower limits of movement of the raking mechanism are reached.

20 36. The combination with a vehicle of an endless rake mounted so as to be capable of swinging bodily about an axis passing through one end of the same in proximity to the rear end of the vehicle, a rotatable 25 shaft mounted on the vehicle in rear of the rake, elongated rollers supported by the vehicle above and parallel with said shaft, and supporting cables passing from said rake over said rollers and having their ends 30 wound upon said shaft.

37. The combination with a vehicle of an endless rake mounted so as to be capable of swinging bodily about an axis passing through one end of the same in proximity 35 to the rear end of the vehicle, a rotatable shaft mounted on the vehicle in rear of the rake, elongated rollers supported by the vehicle above and parallel with said shaft, a pulley adjacent to one end of and co-axial 40 with each of said rollers, pulleys movable with the rake, and supporting cables each passing from an anchoring point on the rake over one of the pulleys adjacent to one of the rollers and then back over the corresponding pulley on the rake and across the 45 corresponding roller and to the aforesaid shaft upon which the free end is wound.

38. The combination with a vehicle, of mechanism adapted to rake the top of the 50 load toward one edge of the vehicle, means for automatically lowering said mechanism to keep it in contact with the diminishing load, and manually-controlled means for arresting the downward movement of said mechanism at any desired point.

39. The combination with a vehicle, of a mechanism including an endless rake adapted to rake the top of the load toward one edge of the vehicle, means for driving 60 the rake continuously, and means for automatically lowering said mechanism step by step.

40. The combination with a vehicle, of a mechanism adapted to rake the top of the 65 load toward one edge of the vehicle, and

means for raising and lowering said mechanism and automatically arresting it at the two limits of its movement, and means for manually arresting the up and down movements of said mechanism at any desired point between said limits.

41. A vehicle with a conveyer mounted so as to rake the top of the load from one end to the other of the vehicle, said conveyer being provided with raking teeth of various lengths.

42. A wheeled vehicle having a conveyer mounted so as to rake the top of the load from one end to the other of the vehicle, 80 said conveyer being provided with short raking pins or teeth and long pins or teeth adapted to enter deeply into the load to loosen up the surface.

43. A wheeled vehicle having a raking conveyer mounted thereon so as to rake the top of the load toward one edge of the vehicle, a beater wheel arranged adjacent to said edge, said raking conveyer and said beater wheel each having pins or teeth of various lengths.

44. In a vehicle, a wheeled body or rack having the wheels mounted so as to prevent relative vertical movements between the same and the adjacent portions of the body or rack, a swinging frame hinged at its rear end near the bottom of the rear end of the body or rack, said swinging frame having a width approximately equal to the width of the body or rack and being of considerable length, an endless raking conveyer mounted on said swinging frame, the body or rack and the swinging frame being so jointed that they will yield when the vehicle is passing over irregular ground so as to accommodate themselves to the irregularities of surface without straining or binding.

45. In a vehicle, a body or rack, an endless rake mounted so as to swing bodily up and down in the body or rack about an axis passing through one end of the endless rake structure and through one end of the body or rack, and guiding shoes on the sides of the free end of the endless rake structure adapted to engage with the sides of the body or rack in order to hold the endless rake properly centered during its up and down movements.

46. A vehicle having a body or rack provided with rearwardly projecting yieldable fingers at the rear end of the bottom thereof, a beater wheel revolubly mounted in rear of and in proximity to said fingers and having pins or teeth adapted to pass through the spaces between the fingers.

47. A vehicle having a body or rack provided with rearwardly extending yieldable fingers at the rear end of the bottom thereof, a beater wheel mounted in rear of said fingers and provided with pins or teeth adapted to pass through the spaces between

5 said fingers, means for rotating the beater wheel so as to cause the pins or teeth to travel downwardly while passing between said fingers, and means for positively feeding material from a load in the body or rack toward the beater wheel.

10 48. In a vehicle, a body or rack having the rear end of the bottom formed of rearwardly projecting fingers, a raking conveyer mounted in the body or rack so as to feed the top of the load rearwardly upon said fingers, a beater wheel mounted in rear of said fingers and having pins or teeth projecting through the spaces between the teeth, 15 and means for rotating the beater wheel in a direction to cause the teeth or pins to travel downwardly while passing between said fingers.

20 49. In a vehicle, a body or rack open at one end, a comb or guard arranged above the rear end of the bottom of the body or rack and having downwardly projecting fingers terminating in the vicinity of the plane of the bottom of the body or rack, a beater wheel arranged in rear of said comb and having pins or teeth adapted to project through the same, and means for positively feeding material from a load in the body or rack against said comb.

25 50. In a vehicle, a body or rack open at one end, a comb or guard arranged above the rear end of the bottom of the body or rack and having downwardly projecting fingers terminating in the vicinity of the plane of the bottom of the body or rack, a beater wheel arranged in rear of said comb and having pins or teeth adapted to project through the same, means for positively feeding material from a load in the body or rack 35 against said comb, and means for causing the beater wheel to rotate in the direction to make the pins or teeth travel downwardly while passing through the spaces between said fingers.

40 51. In a vehicle, a body or rack open at the rear end, a guard or comb arranged at said rear end and having downwardly projecting fingers extending into proximity to the plane of the bottom of the body or rack,

45 50 a beater wheel arranged behind said guard or comb and having pins or teeth movable downwardly through the spaces in the same, and means for raking the top of the load in the body or rack to said guard or comb.

55 52. In a vehicle, a body or rack having the rear end of the bottom thereof formed of a series of rearwardly projecting yieldable fingers, a guard or comb overlying said fingers and having finger members extending down in proximity to the aforesaid fingers, means for feeding material from the body or rack into the angle formed between the two sets of fingers, and means acting through the spaces between the fingers for discharging the material from the vehicle.

53. In a vehicle, a body or rack having the rear end of the bottom thereof formed of a series of rearwardly projecting yieldable fingers, a guard or comb overlying said fingers and having finger members extending down in proximity to the aforesaid fingers, means for feeding material from the body or rack into the angle formed between the two sets of fingers, a beater wheel arranged in rear of said guard or comb and having pins or teeth projecting through the spaces therein, and means for rotating said beater wheel so as to cause the pins or teeth on the front side thereof to travel downwardly.

70 54. In a machine of the character described, a beater wheel, and a yieldable comb or fingered guard lying in front of the same.

75 55. In a machine of the character described, an endless raking conveyer, a beater wheel in proximity to the conveyer, means for driving the conveyer and the beater wheel so as to cause the portions nearest each other to be moving in opposite directions, 80 and a fingered guard or comb arranged between the conveyer and the beater wheel.

85 56. In a vehicle, a body or rack open at the rear end, a revoluble shaft extending transversely across said rear end, a swinging frame approximately as wide as the body or rack mounted at one end on said shaft, an endless raking conveyer on said swinging frame, driving connections between said conveyer and said shaft, said frame having 90 a member of considerable width extending across the same in close proximity to the shaft to form a guard for the latter.

95 57. The combination with a vehicle, of a raking structure provided with a traveling rake adapted to rake the top of the load toward one edge of the vehicle, a distributer adapted to receive material from the traveling rake, means for actuating the traveling rake and the beater at constant relative speeds, and means for lowering the raking structure at any one of a plurality of speeds relative to the speed of the traveling rake and of the distributer.

100 58. In a vehicle for spreading straw or the like, having a body mounted on wheels and a conveyer for removing the top and rear of the load without moving simultaneously the entire body of the load, in combination with a long and short tooth beater 105 wheel at one end of the body.

110 59. In a vehicle for spreading straw or the like, having a body mounted on wheels and a conveyer for removing the top and rear of the load without moving simultaneously the entire body of the load, in combination with a revolving beater wheel at one end of the body and with adjustable guards resting between said conveying device and said beater wheel.

60. In a vehicle for spreading straw or the like, having a body mounted on wheels and a conveyer for removing the top and rear of the load without moving simultaneously the entire body of the load, said conveyer having protruding teeth of different lengths.
61. In a straw spreading apparatus, a vehicle body, a movable conveyer mounted in the body in position to engage with the top of a load therein, said conveyer having teeth of different lengths distributed throughout the length and breadth of the conveyer.
62. In a vehicle for spreading straw or the like, having a body mounted on wheels and a conveyer for removing the top and rear of the load without moving simultaneously the entire body of the load, said conveyer being flexible sidewise so as to adjust itself to the shape and conditions of the body within which it rests.
63. In a vehicle for spreading straw or

the like; having a body mounted on wheels and a conveyer for removing the top and rear of the load without moving simultaneously the entire body of the load, said conveyer being flexible sidewise so as to adjust itself to the shape and conditions of the body within which it rests, said conveyer having contact points to guide it within the surrounding vehicle body.

64. In a vehicle, a body or rack, an endless rake mounted so as to swing bodily up and down in the body or rack about an axis passing through one end of the endless rake structure and through one end of the body or rack, and guiding means at the free end of the endless rake structure adapted to engage with the sides of the body or rack in order to hold the endless rake properly centered during its up and down movements.

In testimony whereof we sign this specification.

HENRY L. LITCHFIELD.

VICTOR SPEER.
